PREPARATION OF HEXAFLUOROETHANE AND HIGHER FLUOROCARBONS

Franciszek Olstowski, Freeport, and John J. Newport III, Lake Jackson, Tex., assignors to The Dow Chemical Company, Midland, Mich., a corporation of Delaware

Filed July 22, 1958, Ser. No. 750,270
6 Claims. (Cl. 204—62)

This invention relates to a process for the preparation of hexafluoroethane and higher molecular weight fluorocarbons, and more particularly, to the preparation of these fluorocarbons by the electrolysis of a non-volatile molten metal fluoride.

Presently the preparation of fluorocarbons is mainly limited to fluorination of chlorinated or unsaturated hydrocarbons by use of fluorinating agents, such as hydrogen fluoride or fluorinating of saturated hydrocarbons by elemental fluorine. These processes involve handling hazardous materials which are expensive and require special equipment.

In United States Letters Patent No. 785,961, a process for the preparation of carbon tetrafluoride by electrolysis of sodium or potassium fluoride is disclosed. In the process disclosed, a solid carbon anode is used which is surrounded with carbonaceous material, such as charcoal or lampblack, to protect it from disintegration. The charcoal or lampblack is confined by a refractory non-conducting sleeve or container. Upon electrolysis of the particular fluorides at a voltage of 8 volts and a temperature of 1000° C. only carbon tetrafluoride is obtained. The metal fluorides are cheap raw materials. A process whereby hexafluoroethane and higher molecular weight fluorocarbons could be prepared by electrolysis of fused metal fluorides would greatly reduce the production cost of these compounds.

It is, therefore, among the objects of this invention to provide a process for the preparation of hexafluoroethane and higher molecular weight fluorocarbons by the electrolysis of non-volatile molten metal fluorides.

The above and other objects are attained by electrolysis of the non-volatile metal fluoride at a temperature in the range of 600° to 925° C. using an anode consisting of carbonaceous material in particulate form with the individual particles being in electrical contact with each other and an insoluble cathode at a sufficient anode density to liberate a gas at the anode containing fluorocarbons of which at least 10 mole percent is hexafluoroethane and higher molecular weight fluorocarbons.

It has been discovered that when a non-volatile metal fluoride is electrolyzed at a temperature of 600° to 925° C. with an anode consisting of carbonaceous material in particulate form loosely confined at a sufficiently high anode density, hexafluoroethane and higher molecular weight fluorocarbons are liberated at the anode as a product of the electrolysis.

The invention may be more easily understood when the detailed discussion is considered in conjunction with the drawings, in which:

FIGURE 1 diagrammatically illustrates an electrolytic cell in which the invention may be carried out, and

FIGURES 2, 3, 4, and 5 show the effect of the anode current density and temperature of the electrolyte on the composition of the anode gases obtained from the cell.

The electrolytic cell diagrammatically shown in FIGURE 1 comprises a metal tank 1 having a cover plate 2, an electrical non-conducting refractory cylindrical liner 3, such as made from alumina or zirconia, and a carbon lead 4 extending part way into the tank through an opening in cover plate 2. As shown, the cover plate is fastened to tank 1 by means of multiplicity of screws 6 to form a gas-tight seal. Clamps or other means may be used

2

instead of the screws. A pipe 7 is attached to cover plate 2 so that the pipe encompasses an opening 8 in the cover plate and provides a passageway through which the anode gas produced as a product inside of tank 1 may be withdrawn from the tank. Where the carbon lead 4 passes through cover plate 2 an electrical insulating seal 9 is used so that a gas-tight seal is obtained. To the end of the carbon lead 4 not extending into tank 1, an electrical lead 10 is attached through which the current is supplied to the cell. Another lead 11 is electrically connected to the surface of the tank which through a molten cathode 12 at the bottom of the tank completes the circuit for the current flow in the electrolytic cell.

In the operation of the cell, electrolyte 13 is placed in the tank 1 and is heated to a temperature of 600° to 925° C. A metal, inert to the fluoride electrolyte and having a melting point below the electrolysis temperature, such as lead, is placed in the cell. The metal settles to the bottom of the cell contacting the surface of the tank and thus acts as a cathode. The inert metal to act as a cathode is only used where the metal deposited at the cathode is lighter than the electrolyte. Even in this case a molten cathode would not have to be used, but an arrangement in the cell design would have to be made to collect the metal deposited from the top of the electrolyte. The metal fluoride used as electrolyte is added to the cell in an amount such that the level of the electrolyte is below the top of the liner 3. The carbon lead 4 is inserted into the tank through the cover plate until the end of the lead is above the electrolyte. Carbonaceous material 14 which is lighter than the molten electrolyte is placed within the liner 3 on the surface of the electrolyte so that it surrounds and contacts the carbon lead 4. An electrical potential is applied to leads 10 and 11 and the anode gas produced is drawn from within tank 1 through pipe 7 after which the gas is further processed by known methods to recover and separate the particular fluorocarbons. The metal depositing out from the electrolyte is deposited in the molten cathode 12 and later recovered.

In the electrolysis of a molten electrolyte consisting essentially of a metal fluoride which is non-volatile and stable at the temperature of the electrolysis according to the invention, a series of homologous fluorocarbons is obtained as an anode product. The anode product is a gas at the electrolysis temperature and contains fluorocarbons, such as carbon tetrafluoride, hexafluoroethane, and higher molecular weight fluorocarbons. With an anode comprising a particulate carbonaceous material with the individual particles being in an electrical contact with each other, hexafluoroethane and higher fluorocarbons are obtained when the temperature of the electrolyte is 925° C. or below and a sufficiently high anode current density is used.

The effect of temperature is illustrated in FIGURES 2, 3, and 4 which show the composition of the fluorocarbon product obtained in the anode gas as a function of the temperature of the electrolyte at particular anode current densities. FIGURE 5 shows the effect of anode current density upon the composition of the fluorocarbon product obtained at the anode at an electrolysis temperature of 700° C. The details of the tests and data upon which the figures are based are set forth in Example I below. In FIGURES 2, 3, and 4, the abscissa represents the temperature of a lithium fluoride-sodium fluoride mixture electrolyte at which the electrolysis was effected and the ordinate represents the composition of the fluorocarbon product in the anode gas in mole percent.

FIGURE 2 illustrates the composition of the fluorocarbon product obtained as a function of temperature at an anode current density of 1 ampere per square inch. It will be noted that with the electrolyte at 700° C. the

fluorocarbon product obtained contained approximately 30 mole percent of hexafluoroethane. As the temperature of the electrolyte increased, the amount of hexafluoroethane decreased, while the amount of carbon tetrafluoride increased until at 800° C. approximately all of the fluorocarbon product was carbon tetrafluoride.

At an anode current density of 3 amperes per square inch, as shown in FIGURE 3, a maximum production of hexafluoroethane was obtained at a temperature of about 800° C. As the temperature was increased above 800° C. the amount of hexafluoroethane obtained sharply decreased dropping off to less than 20 mole percent at 900° C. Octafluoropropane was obtained at 700° C. but could only be detected at 800° C.

With an anode current density above 3 amperes per square inch, a very pronounced increase in the higher molecular weight fluorocarbons production was obtained as the temperature was increased from 700° to 800° C. This can be seen in FIGURE 4 where the current density was approximately 5 amperes per square inch. A fluorocarbon product containing a maximum amount of hexafluoroethane, approximately 70 percent of the total fluorocarbon product, was obtained at 800° C., while the amount of carbon tetrafluoride obtained decreased to a minimum of around 30 mole percent. The concentration of the hexafluoroethane dropped off very rapidly as the temperature was increased over 900° C.

In FIGURE 5 the composition of the anode fluorocarbon product obtained is shown as a function of the current density during the electrolysis of the lithium fluoride-sodium fluoride mixture at 700° C. The abscissa represents the anode current density in amperes per square inch and the ordinate the composition of the fluorocarbon product in mole percent. The amounts of carbon tetrafluoride, hexafluoroethane, and octafluoropropane are plotted as a function of the current density. From the curves it may be seen that the amount of carbon tetrafluoride decreased as the anode current density was increased, while the amount of hexafluoroethane increased. The maximum amount of octafluoropropane obtained was over 5 mole percent.

While the particular amounts of carbon tetrafluoride, hexafluoroethane, and the higher molecular weight fluorocarbons will vary somewhat with the particular metal fluoride or fluorides employed as the electrolyte, similar results to those shown in the above figures are obtained. A fluorocarbon product containing at least 10 mole percent of hexafluoroethane and higher molecular weight fluorocarbons is obtained at electrolysis temperatures of 600° to 925° C. with the amount of these fluorocarbons decreasing rapidly to practically nil as the temperature is increased above 925° C. Metal fluorides which are non-volatile and stable at the electrolysis temperature may be used as the electrolyte in the production of these fluorocarbons. Alkali metal fluorides, alkaline earth metal fluorides, earth metal fluorides and mixtures thereof may be used. Illustrative examples of these metal fluorides are magnesium fluoride, aluminum fluoride, sodium fluoride, barium fluoride, strontium fluoride, calcium fluoride, lithium fluoride, yttrium fluoride, and cesium fluoride.

Although only one of the alkali metal fluorides, alkaline earth metal fluorides, or earth metal fluorides may be used as electrolyte, a mixture of these metal fluorides is often used to increase the conductivity or may have to be used to lower the melting point of the bath to a temperature below 925° C. For this purpose, lithium fluoride and sodium fluoride are most commonly added to the other metal fluorides, but other mixtures and combinations may also be used. When other fluorides are added to either increase the conductivity or lower the melting point of a particular metal fluoride bath, the fluorides of the metals which are higher in electromotive series or more electronegative than the metal to be extracted at the cathode from the particular bath are pre-

fferred. By using fluorides of metals more electronegative, these metals will not deposit out at the cathode with the desired metal except at an exceptionally high cathode current density. Thus the cathode product is not contaminated under normal operating conditions. Also in continuous operation of the cell, the metal fluoride added to the electrolyte is not depleted by the electrolysis and only the fluoride of the particular metal being deposited at the cathode has to be added continuously. For example, when lithium fluoride is added to a magnesium bath, the lithium is more electronegative than magnesium and thus will not deposit out at the cathode. Once the lithium fluoride is added to the bath it will not be depleted by the electrolysis and only magnesium fluoride has to be added for continuous operation.

Some examples of the metal fluoride mixtures that may be used for the preparation of hexafluoroethane and higher molecular weight fluorocarbons are shown in the table below with the metal which is preferentially deposited at the cathode indicated.

	Electrolyte Composition	Metal Preferentially Deposited at the Cathode
25	NaF-LiF	Na.
	MgF ₂ -LiF	Mg.
	BaF ₂ -LiF	Li.
	AlF ₃ -LiF	Al.
	AlF ₃ -NaF	Al.
	AlF ₃ -NaF-LiF	Al.
30	AlF ₃ -CaF ₂ -MgF ₂	Al.
	MgF ₂ -LiF-NaF	Na.
	MgF ₂ -LiF-CaF ₂	Mg.
	MgF ₂ -NaF	Na.
	AlF ₃ -LiF-MgF ₂	Al.
	YF ₃ -LiF	Y.

The term "earth metals," as used herein, means the elements aluminum, scandium, yttrium, and lanthanum of the third group of the periodic system.

While generally the desired electrolysis temperature is the same for all of the metal fluorides or mixtures used, the optimum temperature for particular electrolytes may vary to a certain degree. The temperature of the bath must not exceed 925° C. so that the electrolyte used in the cell must have a melting point below this temperature. Metal fluorides which are operative in the cell but have melting points above 925° C. must be thus combined with other metal fluorides to lower the melting point of the bath. As may be seen from the plots of FIGURES 2-5, lower temperatures are preferred. The employment of lower temperature will result in the production of more of the higher molecular weight fluorocarbons. While the maximum production of hexafluoroethane may be obtained at temperatures in the range of 750° to 850° C., higher fluorocarbons such as octafluoropropane are only obtained in appreciable amounts at a temperature below 800° C. Thus, for the production of higher molecular weight fluorocarbons than hexafluoroethane a temperature of 600° to 700° C. is desirable. The optimum production of hexafluoroethane and higher fluorocarbons is generally obtained for most of the metal fluoride electrolytes at a temperature in the range of 725° to 825° C.

As may be also seen from FIGURES 2-5, the anode current density necessary to produce a fluorocarbon product containing at least 10 percent of hexafluoroethane and higher molecular weight fluorocarbons varies with the temperature of the electrolyte. At 700° C. the anode product obtained at practically any anode current density contains at least 10 percent hexafluoroethane and higher molecular weight fluorocarbons. This is specifically shown in FIGURE 5. As the temperature of the bath or electrolyte is increased, the anode current density necessary to produce a fluorocarbon stream containing the desired amount of hexafluoroethane and higher fluorocarbons increases. At 800° C. an anode current density of approximately 1.5 amperes per square inch is required,

while at 900° C. the minimum anode current density is approximately 3 amperes per square inch. The particular anode current density required at a given temperature to obtain a stream containing at least 10 percent of hexafluoroethane and higher fluorocarbons will vary somewhat with the particular electrolyte used in the bath. However, with all of the electrolytes a lower anode current density may be used to obtain the higher fluorocarbons at lower temperatures. The cathode current density generally employed is in the range of 1 to 30 amperes per square inch.

Since the anode in the cell comprises carbonaceous material in particulate form loosely confined, it is difficult to accurately determine the area of the anode contacting the electrolyte. In determining the "anode current density," as herein expressed, the anode area is considered to be equal to the area of the electrolyte upon which the carbonaceous material floats. Since the carbonaceous material is considerably lighter than the electrolyte, the bed of the carbonaceous material remains substantially on the surface of the electrolyte with very little of the carbonaceous material being immersed in the electrolyte. Thus, in determining the anode current density, the total cell current in amperes is divided by the area of the electrolyte subjected to the carbonaceous material in square inches.

Practically any carbonaceous material in particulate form may be used. Charcoal, coke, lampblack, powdered carbon, and powdered graphite are illustrative examples of some of the carbonaceous materials which are operative. Due to its availability, coke in particulate form is preferred. Generally, particles of carbonaceous material larger than 1 inch are not used except in a large unit where a large bed is employed. Particles as small as those passing through a No. 100 standard mesh screen and being retained on No. 300 mesh screen or lampblack are operative. However, generally it is preferred to use carbonaceous material which will pass through a No. 6 standard mesh screen and be retained on a No. 40 standard mesh screen.

The voltage used is such that sufficient anode current density is obtained to give a product containing at least 10 percent hexafluoroethane and higher molecular weight fluorocarbons. The actual voltage necessary to obtain the desired anode current density will vary with the temperature, the carbonaceous material, anode to cathode separation and the metal fluoride or mixtures of metal fluorides used in the electrolysis. However, a higher voltage is used at a higher electrolysis temperature, since a larger anode current density is required. At a bath temperature of around 700° C. a voltage of approximately 5 volts may

which do not have a vapor pressure in excess of 10 millimeters of mercury at the electrolysis temperature and which do not decompose due to heat alone at the electrolysis temperature.

5 The following example further illustrates the invention but is not to be construed as limiting it thereto.

Example 1

10 A series of runs was made where an electrolyte consisting essentially of 48 percent of lithium fluoride and 52 weight percent sodium fluoride was subjected to electrolysis at different anode current densities and different temperatures. A cell similar to that shown in FIGURE 1 was used. The tank was approximately 6 inches in diameter and an alumina liner was inserted which was 3 inches in diameter and 5 inches high. The carbon lead extending through the cover of the tank was a $\frac{3}{4}$ inch graphite rod.

15 In the operation of the cell, lead which was to act as a molten cathode and 1000 grams of a mixture containing 48 weight percent of lithium fluoride and 52 weight percent of sodium fluoride were placed in the cell inside of the alumina liner and heated to melt the electrolyte. The $\frac{3}{4}$ inch graphite rod was extended into the cell until it 20 almost touched the surface of the electrolyte. The carbonaceous material was placed on top of the electrolyte to form a bed 2 inches thick within the alumina liner and surrounding the $\frac{3}{4}$ inch graphite rod. In one of the runs lampblack was used as a carbonaceous material and in 25 the remaining runs petroleum coke passing through $\frac{1}{8}$ inch mesh screen and being retained on a number 40 mesh standard screen was used. The cover was placed on the tank and tightened to obtain a gas-tight seal.

30 The cell was then placed in the furnace where the metal fluoride electrolyte and lead cathode were heated to a predetermined temperature. When the electrolyte reached the desired temperature, current was passed through the cell at a given voltage to produce the desired anode current density. The anode product being produced was drawn off from inside the cell through a gas 35 exit line in the cover of the tank similar to that indicated as number 7 in FIGURE 1. The cell was operated for 1 hour during which time the anode gas issuing from the cell was collected. It was analyzed by infrared analysis 40 or by vapor phase chromatography from which the composition of the fluorocarbon product obtained was determined.

45 The results obtained and the pertinent data of the runs made are shown in the table below. The results of these runs were used to obtain the curves shown in FIGURES 2, 3, 4, and 5.

be sufficient to give the required anode current density, while at 900° C. a voltage of from 9 volts to as high as 30 volts may have to be used.

The term "non-volatile and stable," as herein used in reference to the metal fluoride, means metal fluorides

75 In a manner similar to that above a fluorocarbon product from the anode may be obtained containing at least 10 mole percent of hexafluoroethane and higher fluorocarbons by electrolysis of other alkali metal fluorides, alkaline earth metal fluorides, and earth metal fluorides

which are non-volatile and stable at the temperature of the electrolysis as well as mixtures of these metal fluorides.

What is claimed is:

1. A process for the preparation of a fluorocarbon anode product containing hexafluoroethane and higher molecular weight fluorocarbons, which consists of passing an electric current at a voltage up to as high as 30 volts through a molten electrolyte at a temperature in the range of 600° to 925° C., between an anode consisting of carbonaceous material in particulate form, the individual particles being in electrical contact with each other, and an insoluble cathode at a sufficient anode current density to liberate a gas at the anode containing fluorocarbons of which fluorocarbons at least 10 mole percent is hexafluoroethane and higher molecular weight fluorocarbons such that for electrolyte temperatures above 700° C. the minimum anode current density is increased with an increase in temperature of the electrolyte so that at 800° C. the minimum anode current density is 1.5 amperes per square inch and at 900° C. the minimum anode current density is 3 amperes per square inch, said molten electrolyte consisting essentially of at least one metal fluoride which is stable and non-volatile at the electrolysis temperature selected from the group consisting of alkali metal fluorides, alkaline earth metal fluorides, and earth metal fluorides.

2. A process according to claim 1 wherein the molten electrolyte consists essentially of at least one alkali metal fluoride which is stable and non-volatile at the electrolysis temperature.

3. A process according to claim 1 wherein the tempera-

ture is in the range of 725° to 825° C. and the carbonaceous material is petroleum coke.

4. A process for the preparation of a fluorocarbon anode product containing hexafluoroethane and higher fluorocarbons, which consists of passing an electric current at a voltage up to as high as 30 volts through a molten electrolyte consisting essentially of a mixture of sodium fluoride and lithium fluoride at a temperature in the range of 600° to 925° C., between an anode consisting of carbonaceous material in particulate form, the individual particles being in electrical contact with each other, and an insoluble cathode at a sufficient anode current density to liberate a gas stream at the anode containing fluorocarbons of which at least 10 mole percent is hexafluoroethane and higher molecular weight fluorocarbons such that for electrolyte temperatures above 700° C. the minimum anode current density is increased with increase in temperature of the electrolyte so that at 800° C. the minimum anode current density is 1.5 amperes per square inch and at 900° C. the minimum anode current density is 3 amperes per square inch.

5. A process according to claim 4 wherein the temperature is in the range of 725° to 825° C. and the anode current density is from 3 to 5 amperes per square inch.

6. A process according to claim 4 wherein the carbonaceous material is petroleum coke.
